UNITED STATES PATENT OFFICE

97,349

DESIGN FOR A BOOTH OR SIMILAR ARTICLE

Lawrence M. Hampton, Northfield, N. J.

Application September 22, 1934, Serial No. 53,374

Term of patent 3½ years

To all whom it may concern:

Be it known that I, Lawrence M. Hampton, a citizen of the United States, residing at Northfield, New Jersey, have invented a new, original, and ornamental Design for a Booth or Similar Article, of which the following is a specification, reference being had to the accompanying drawing, forming part thereof.

The figure is a perspective front view of a

booth or similar article, showing my new design, the base portion representing flames licking up the side of the article.

The other side of the booth is of plain log character.

I claim:

The ornamental design for a booth or similar article, substantially as shown and described.

LAWRENCE M. HAMPTON.
